TENNIS POST CAP

Brian Frederick Hirst, Halifax, England, assignor to
B. Hirst & Sons Limited

Filed Oct. 23, 1973, Ser. No. 408,563

Term of patent 14 years

Int. CL. D25—01

U.S. CL. D28—1 C

FIG. 1—

FIG. 4—

FIG. 2—

FIG. 5—

FIG. 3—

FIG. 6—

FIG. 1 is an end view of a tennis post cap incorporating my design.

FIG. 2 is a top plan view thereof.

FIG. 3 is a bottom plan view thereof.

FIG. 4 is a side elevational view thereof.

FIG. 5 is a side elevational view thereof taken from the side opposite that shown in FIG. 4.

FIG. 6 is a sectional view thereof taken on the line VI—VI of FIG. 2.

The end opposite that shown in FIG. 1 is identical to the view shown.

I claim:

The ornamental design for a tennis post cap, substantially as shown and described.
